US0D1089468S

(12) **United States Design Patent** (10) **Patent No.:** **US D1,089,468 S**
(45) **Date of Patent:** **** Aug. 19, 2025**

(54) **BALANCE BOARD**

(71) Applicant: **Shenzhen HYTD Technology Co., Ltd.**, Shenzhen (CN)

(72) Inventor: **Chengting Hu**, Shenzhen (CN)

(73) Assignee: **Shenzhen HYTD Technology Co., Ltd.**, Shenzhen (CN)

(**) Term: **15 Years**

(21) Appl. No.: **29/973,256**

(22) Filed: **Nov. 14, 2024**

(30) **Foreign Application Priority Data**

Apr. 23, 2024 (CN) 202430232955.4

(51) **LOC (15) Cl.** **21-02**

(52) **U.S. Cl.**

USPC **D21/686**; D21/671

(58) **Field of Classification Search**

USPC D19/88; D21/662, 671, 686, 688, 692
CPC A63B 22/18; A63B 22/16; A63B 26/003;

(57) **CLAIM**

The ornamental design for a balance board, as shown and described.

DESCRIPTION

FIG. 1 is a front perspective view of a balance board, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view showing the balance board in a state; and,

FIG. 10 is a rear view showing the balance board in a state. The broken lines in the drawings illustrate the portions of the balance board, which form no part of the claimed design.

1 Claim, 10 Drawing Sheets
